CLAIM

The ornamental design for a housing for an electronic sampling and measuring device, as shown and described.

DESCRIPTION

FIG. 1 is a front-elevated perspective view of a housing for an electronic sampling and measuring device showing my new design;

FIG. 2 is a front view of the housing for an electronic sampling and measuring device of FIG. 1;

FIG. 3 is a rear view of the housing for an electronic sampling and measuring device of FIG. 1;

FIG. 4 is a top plan view of the housing for an electronic sampling and measuring device of FIG. 1;

FIG. 5 is a bottom view of the housing for an electronic sampling and measuring device of FIG. 1;

FIG. 6 is a side view of the housing for an electronic sampling and measuring device from the right of FIG. 1; and,

FIG. 7 is a side view of the housing for an electronic sampling and measuring device from the left of FIG. 1.
